UNITED STATES PATENT OFFICE.

CHARLES EUGENE BRINEY, OF COVINGTON, KENTUCKY.

WINDOW-SCREEN LATCH.

Application filed July 1, 1922. Serial No. 572,125.

To all whom it may concern:

Be it known that I, CHARLES E. BRINEY, a citizen of the United States, residing at Covington, in the county of Kenton and 5 State of Kentucky, have invented new and useful Improvements in Window-Screen Latches, of which the following is a specification.

The object of my present invention is the 10 provision of an improved construction embracing a lower slideable window sash, and a window screen, and means under the control of an operator whereby when desired the sash may be coupled to the screen so that 15 raising of the lower sash will be attended by elevation of the screen into working position, while lowering of the lower sash will be attended by a disposition of the screen in a pocket provided for its accommodation 20 whereupon if deemed expedient as in the winter time, the lower sash may be uncoupled from the screen so that the said lower sash may be raised or lowered at will in the ordinary well known manner without 25 any movement whatever of the screen.

To the attainment of the foregoing, the invention consists in the improvement as hereinafter described and definitely claimed.

In the accompanying drawings, forming 30 part of this specification:—

Figure 1 is a view showing my improvement with the lower sash and the screen in their lower positions.

Figure 2 is a similar view of the lower 35 sash and the screen raised.

Figure 3 is an enlarged detail section on the line 3—3 of Figure 1.

Figure 4 is an enlarged detail section at right angles to Figure 3 and on the line 40 4—4 of said figure.

Figure 5 is a broken plan view of the upper edge of the screen.

Similar numerals of reference designate 45 corresponding parts in all of the views of the drawings.

In furtherance of my invention the window casing 1 is provided with a pocket 2 arranged below and in the same vertical plane as the lower sliding sash 3, and in 50 the said pocket is adapted to be arranged a rectilinearly movable screen 4. In the upper bar of its frame the said screen 4 is provided with pockets 5, and attached to the said upper bar and arranged over the 55 said pockets 5 are flush plates 6 with aper-

tures 7 and cross bars 8, one cross bar to each plate.

Also in furtherance of my invention the lower sash 3 is provided in its lower frame bar with chambers 9 one of which is clearly 60 shown in Figure 4. It will also be noticed that the lower sash is equipped with headed bolts 10 of angular form in cross section, the said headed bolts being introduced through openings 11 in the outer side of 65 the sash bar and arranged at right angles to the chambers 9 and having their inner ends disposed and fastened in rotary caps 12 opposed to the inner side of the lower sash bar and equipped with handles 13. 70 Keyed on the bolts 10 are latch arms 14 and mounted on the bolts 10 and interposed between the heads thereof and the outer sides of the latch arms 14 are coiled springs 15. These springs 15 are designed and adapted 75 to impose such tension on the latch arms 14 that the said latch arms 14 will rest in their upper idle positions in the chambers 9 when the latch arms are adjusted to such idle positions. 80

In the practical use of my improvement it will be manifest that when the handles 13 are in upright positions as shown in Figures 2, 3 and 4, the latch arms 14 by co-operation with the plates 6 will couple the 85 screen 4 to the lower sash 3, and hence upward movement of the sash 3 will be attended by the upward movement of the screen 4 so that the said screen will effectively bar the opening left by the raising 90 of the sash 3. Likewise when the sash 3 is lowered to closed position the screen 4 will be moved down into the pocket 2 and entirely out of the way as well as entirely out of sight. When the handles 13 are 95 turned to horizontal positions as appears in Figure 1, it will be understood that the latch arms 14 will rest idly in their upper positions in the chambers 9, and hence the sash 3 and the screen 4 will be uncoupled with 100 the result that the sash may be raised and lowered in the ordinary manner without any movement whatever of the screen. This uncoupling feature is particularly advantageous for use in the winter time when 105 screens are obviously unnecessary. It will be noted, however, that whenever it is desired to couple the screen 4 to the sash 3 the same may be accomplished while the sash 3 is in its lower position by simply 110

turning the handles 13 to vertical position. It will be apparent from the foregoing that the parts of my improvement are susceptible of being quickly and easily assembled, and that all parts of the improvement are well adapted to withstand the usage to which sash appurtenances are ordinarily subjected.

It will also be appreciated that the parts 10 of my improvement are calculated to enhance rather than detract from the finished appearance of the lower sash.

I have entered into a detailed description 15 of the construction and relative arrangement of the parts embraced in the present and preferred embodiment of my invention in order to impart a full, clear and exact understanding of the said embodiment. I do not desire, however, to be understood as 20 confining myself to the specific construction and relative arrangement of parts inasmuch as in the future practice of the invention various changes and modifications may be

made such as fall within the scope of my invention as defined in my appended claim. 25

Having described my invention, what I claim and desire to secure by Letters Patent, is:—

A window screen latch including a square headed member rotatable transversely of one side member, a handle removably mounted on one end of said headed member having a face for bearing contact with the sash member, a latch arm slidable on the headed member and adapted for rotation therewith to engage or disengage a keeper mounted on a cooperating sash member, and a coil spring mounted on the headed member between the latch arm and the head for normally holding said latch arm in bearing contact with the sash member in opposed relation to the handle. 30 35 40

In testimony whereof, I affix my signature.

CHARLES EUGENE BRINEY.
